NON-PERMANENT RADIATION SHIELD
STRUCTURE

Thomas J. O'Connell, Clinton, Md., assignor to the United States of America as represented by the Secretary of the Navy

Filed Nov. 7, 1955, Ser. No. 545,583

4 Claims. (Cl. 250—108)

(Granted under Title 35, U.S. Code (1952), sec. 266)

The invention described herein may be manufactured and used by or for the Government of the United States of America for governmental purposes without the payment of any royalties thereon or therefor.

The present invention relates to interlocking shielding blocks and more particularly to a movable, non-permanent radiation shield structure for "hot" laboratories or equipment.

It is customary and necessary to protect people and equipment from harmful effects of certain radiation. Protection, heretofore, has generally been made with permanent structures in the form of walls, ceilings and floors in or on which a sheet of lead has been placed. The present invention affords a means of constructing a non-permanent shield of interlocking blocks made of a radiation absorption or shielding material having a thickness great enough to prevent penetration of harmful radiation and also thick enough to support itself. These blocks have matching male and female surfaces such that they do not need any extra material between the joints to maintain the blocks in a desired position or to prevent radiation from penetrating the joints.

An object of the present invention is to form a movable, non-permanent radiation shield structure.

A further object of the present invention is to provide a non-permanent shield structure which is self-supporting.

Still another object of the present invention is to provide a radiation shield structure with a plurality of interlocking faces along adjoining end surfaces.

A still further object of the present invention is to provide a shield block structure with adjoining surfaces which interlock on turning corners as well as along a straight line wall.

Other and more specific objects of this invention will become apparent upon a careful consideration of the following detailed description when taken together with the accompanying drawings, in which:

Fig. 1 is a sectional view through a preferred modification of this invention,

Fig. 2 is a perspective view of a partial shield structure comprising blocks as shown in the modification (Fig. 1),

Fig. 3 is a sectional view through another modification, and

Fig. 4 is a perspective view of a partial shield structure comprising blocks as shown in the modification (Fig. 3).

Referring to the shield structure as shown in Figs. 1 and 2 there are blocks 10 made of cement of any other desired radiation absorption material. The blocks 10 have straight edge vertical and horizontal surfaces, vertical end surfaces 11 and 12 of each block are provided with a plurality of equal rectangular faces of which the illustrated block has three faces on each end surface, the ends forming respectively male and female end surfaces. The three faces on the male end surface are formed parallel with the faces on the female surface wherein the central face is formed at a 90 degree angle to the side surfaces and the other two faces on each end are formed at 45 degree angles to the side surface and meeting the

2

central face wherein a 135 degree angle is formed between any two faces of each respective end. When placed end to end, successive blocks interfit with surface 11, the male end, of one block adjoining surface 12, the female end, of the next successive block to form an interlocking joint to eliminate "through" cracks at the joints. The construction of the end surfaces of the blocks are for stability and to insure against any radiation passing therethrough.

- 10 It is obvious that radiation would enter the smallest crack between end surfaces but this would be prevented from penetrating the block by the thickness of the block at the point the radiation hits the block. As shown at 9 in Fig. 1; the thickness of the block in a straight line from the point that radiation entering the crack hits the block is the same distance to a side surface as the thickness of the block; therefore, any radiation entering the crack would be shielded from passing through the block since it cannot turn the corner to follow the crack. The 15 faces of surface 12 fits along the faces of surface 11 in such a manner that radiation cannot pass because the radiation cannot bend around the angular corner of the joint formed by the adjoining faces of the two end surfaces. When turning corners one block is positioned at 20 a 45° angle with its preceding adjacent block and the next block is positioned at a 45° angle to that block, this constitutes a 90° turn and makes a radiation tight wall with the faces of the adjacent end surfaces providing a 25 tight interlocking fit.
- 30 The modifications shown in Figs. 3 and 4 are similar to the above disclosed blocks wherein the interlocking faces are cut on a 45° angle such that adjacent blocks match and constitute a radiation shielding wall surface. As shown one of the blocks 21 is made with equiangular disposed rectangular faces such that a polyhedron is formed with eight sides having an angle of 135° between adjacent faces. The adjoining mating block 22 is formed with two identical female surfaces 23 and 24 that have three equal 35 rectangular faces on each surface, said surfaces match the faces of block 21 to form a radiation tight joint, as explained above. It is obvious that the polyhedron must have a certain width across opposite faces and the block 22 must be the same width but there is no limit to the 40 length between the surfaces 23 and 24 since it is the faces of the surfaces 23 and 24 that must interlock with the matching faces of the polyhedron and be equal thereto. The faces of surfaces 23 and 24 are cut or formed with the central faces at a 90 degree angle to the side surfaces and the outer two faces are on a 45 degree angle, such 45 that they converge toward the central face to form female end surfaces. These end faces then match the faces on the polyhedron to make a radiation shielding joint. The polyhedron 21 in effect forms two male surfaces that mates with the ends of two adjacent female end surfaces of two separate blocks 22.
- 50 In each of the modifications shown the block surface comprising the faces must be vertical and the height is limited by the thickness, to be self-supporting. The blocks can be made for any desired height and thickness, the thickness being preferably large enough to make the 55 assembled shield self-supporting. The blocks are placed with their matching interlocking male and female faces together and since the faces fit so closely together in an interlocking position the shield will be self-supporting without bonding the matching surfaces; therefore, the shield can be a non-permanent structure and adjusted to changing requirements.

The blocks are positioned end to end with the male and female surfaces matching to form a joint that will shield radiation. In the modification shown in Figs. 1 and 2 all blocks have the same shape and opposite faces on each end surface are made parallel; so, when the blocks

are positioned end to end the male and female faces match and interlock to form a close fit. In the modification of Figs. 3 and 4, alternate blocks have the same configuration and the face surfaces of one block matches the face surface of the adjacent block. In this modification it is necessary to have two different shaped blocks whereas, in the modification of Figs. 1 and 2, each block has the same configuration and the end of one block matches an end of another like block. The angle of the faces are such that in turning corners the blocks are positioned at 45 degree angles to each other and it is necessary to make two such angular joints to complete a 90 degree turn. This shield structure can be quickly disassembled or any portion could be changed by merely removing blocks at the desired location without interfering with the remaining blocks.

In event the blocks are made of cement or a like material the blocks can include reinforcing rods cast into the column itself to aid the column in supporting its own weight while in an upright position; also, reinforcing beads may be inserted along the outer surface edges of the end surfaces to prevent chipping, etc. Eye bolts or eye bolt receptacles may be cast on the center of gravity axis to facilitate movement with a crane.

Obviously many modifications and variations of the present invention are possible in the light of the above teaching. It is therefore to be understood, that within the scope of the appended claims, the invention may be practiced otherwise than as specifically described.

What is claimed is:

1. A movable, non-permanent, self-supporting shield structure for harmful radiation comprising radiation absorption blocks having substantially parallel side surfaces and matching male and female end surfaces each formed by at least three equiangularly disposed rectangular faces of equal dimensions, the angles between adjacent faces at the end surfaces being equal to about 135 degrees, the angle formed by a side and the adjacent faces on the male end surface being about 135° and the angle formed by a side and the adjacent end surface of the female end surface being about 45°, said male and female end surfaces of said absorption blocks being adapted to be positioned in matching end to end abutting relationship with their center lines linearly disposed to form a straight uniform wall surface and adapted to be matched angularly at their end surfaces relative to each other to form a second wall structure with abutting surfaces disposed at an angle to said first mentioned wall surface to provide a radiation shield structure with no through cracks, said matching end surfaces providing sufficient thickness at their junction to prevent radiation passage through the crack at the abutting end surfaces.

2. A movable, non-permanent, self-supporting shield

structure for harmful radiation comprising radiation absorption blocks each having substantially parallel side surfaces and male and female end surfaces, said male and female surfaces being formed by at least three equiangularly disposed rectangular faces of equal dimensions and disposed at an angle of about 135 degrees relative to each other, said absorption blocks adapted to be placed in a matching end to end abutting position with their center lines linearly disposed to form a straight uniform wall structure and adapted to be angularly disposed relative to each other in an abutting position to form a second wall surface at an angle to said first mentioned wall surface to provide a radiation shield structure with no through cracks, said matching end surfaces providing sufficient thickness at their junction to prevent radiation passage through the crack at the abutting end surfaces.

3. A movable, non-permanent, self-supporting shield structure for harmful radiation comprising first and second radiation absorption blocks having matching male and female end surfaces with each of said blocks having substantially parallel side surfaces, said male surfaces being formed on the end surfaces of said first block, said female surfaces being formed on the end surfaces of said second block, said end surfaces on each of said blocks being formed by at least three equiangularly disposed rectangular faces of equal dimensions and disposed at an angle of about 135 degrees relative to each other, said blocks adapted to be alternately positioned in matching end to end abutting relationship with their center lines linearly disposed to form a straight uniform wall surface and adapted to be positioned angularly in matching abutting relationship to form a second wall surface at an angle to said first mentioned wall surface to provide a radiation shield structure with no through cracks, said matching end surfaces providing sufficient thickness at their junction to prevent radiation passage through the crack at the abutting end surfaces.

4. A movable, non-permanent, self-supporting shield structure for harmful radiation as claimed in claim 1 in which each of said blocks includes an eye bolt in the upper surface on the center of gravity axis to facilitate movement of said blocks.
